UNITED STATES PATENT OFFICE.

BERNHARD E. FERNOW, JR., OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC BRAKE.

Application filed July 2, 1921. Serial No. 482,071.

To all whom it may concern:

Be it known that I, BERNHARD E. FERNOW, Jr., a citizen of the United States, residing at Milwaukee, in the county of Milwaukee and State of Wisconsin, have invented new and useful Improvements in Electromagnetic Brakes, of which the following is a full, clear, concise, and exact description, reference being had to the accompanying drawing, forming a part of this specification.

This invention relates to improvements in electro-magnetic brakes.

The invention is particularly applicable to brakes of the character disclosed in my Patent No. 1,410,395 of March 21, 1922, and relates more particularly to means for equalizing the releasing movements of the shoes of such brakes.

The brake disclosed in said application is designed for mounting in a position wherein the field and armature members of the magnet tend to move away from the drum under the influence of gravity and the same is provided with an adjustable stop for effecting equalization of the releasing movements of the brake levers when the brake is so mounted. However, if the brake is mounted in a position wherein the armature and field members tend to move towards the drum under the influence of gravity such stop will permit the shoe associated with the armature member to remain in engagement with the drum, and the present invention has among its objects to provide means for equalizing the releasing movements of the shoes when the brake is so mounted.

Another object is to provide means of the aforesaid character which can be readily applied to the brake without materially altering the construction of the parts thereof.

Various other objects and advantages of the invention will hereinafter appear.

The accompanying drawing illustrates certain embodiments of the invention and the same will now be described, it being understood that the embodiments illustrated are susceptible of various modifications without departing from the scope of the appended claims.

In the drawing,

Fig. 1 is a side elevational view of a brake embodying the invention, the electromagnet being shown partially in section;

Fig. 2 is a top plan view of Fig. 1; and Fig. 3 is a side elevational view of a brake embodying the invention in a modified form.

Referring to the drawing the same illustrates a brake drum 1 to be secured to the motor or other device to be braked, opposed brake shoes 2 and 3 to frictionally engage said drum and levers 4 and 5 supporting said shoes respectively. The levers 4 and 5 have pivots 6 and 7 respectively on a base 8 and shoes 2 and 3 have pivots 9 and 10 respectively on said levers in line with the center of the drum, said levers being provided with adjustable stops 11 and 12 respectively for the lower ends of said shoes.

The lever 5 is provided with a circular portion 13 to be attracted by an annular field member 14, said field member being provided with an annular winding 15 and being pivotally supported by lugs 16 and 17 on the pivot pin of lever 5. Lever 5 and field member 14 are biased apart by a spring 18 and the free end of lever 4 is connected to the free extremity of said field member by a link connection 19. Spring 18 accordingly serves to set the brake shoes 2 and 3 against drum 1 and energization of winding 15 serves to attract lever 5 and field member 14 towards each other for spreading of said shoes.

However, if the brake is mounted as shown in Fig. 1, that is, with the parts of the magnet located above drum 1, it is apparent that upon energization of the magnet, field member 14 and lever 5 will tend to move downwardly under the influence of gravity. Unless downward movement of said field member is limited, shoe 3 will be held in engagement with drum 1 by the weight of the magnet parts while shoe 2 will move away from drum 1 to a degree corresponding to the total movement of said field member.

For equalizing the releasing movements of shoes 2 and 3 field member 14 has an adjustable stop 20 associated therewith, said stop being carried by an arm 21 secured to lug 16 of field member 14 and being arranged to engage a projecting lug 22 on base 8. Stop 20 is normally out of engagement with lug 22 and the same is set to arrest field member 14 in a position wherein lever 5 will be attracted upwardly to a degree substantially equal to the degree of downward movement of said field member. Since the relative movement of shoes 2 and 3 is sub-

stantially equal to the relative movement of the members of the electro-magnet it is apparent that stop 20 serves to equalize the releasing movements of said shoes.

5 In certain installations it is desired to mount the brake in a position wherein the base is slightly tilted as shown in Fig. 3. In such installations a stop of lighter construction than that shown in Fig. 1 can be 10 employed since it is not necessary to support the entire weight of field member 14 when limiting movement thereof towards drum 1. As shown in Fig. 3, base 8 is provided with a projecting lug 23 at one end thereof, 15 said lug being provided with an adjustable stop 24 for engaging brake lever 4. Stop 24 is adjusted to permit the desired releasing movement of brake lever 4 and the same acts through said lever and the connection 20 19 to limit movement of the field member 14 towards drum 1. In other words, stop 24 performs the same function as the stop described in connection with Fig. 1.

What I claim as new and desire to secure 25 by Letters Patent is:

1. The combination with a brake drum and opposed brake shoes therefor of an electromagnet having field and armature members, said members being movable independently of each other and upon brake 30 release tending to move towards said drum under the influence of gravity and means associated with one of said members to limit movement thereof towards said drum, 35 said means being adjustable to provide substantially equal movements of said brake shoes by said electromagnet.

2. The combination with a brake drum and opposed brake shoes therefor, of an electromagnet having relatively movable pivoted 40 parts each connected to one of said brake shoes, said parts upon brake release tending to move towards said drum under the influence of gravity and a stop associated with one of said magnet parts for limiting movement thereof towards said drum, said stop insuring substantially equal movements of 45 said brake shoes by said electromagnet.

3. The combination with a brake drum and opposed brake shoes therefor, of a supporting base, an electromagnet having relatively movable field and armature members pivotedly secured to said base, said members upon brake release tending to move towards 50 said drum under the influence of gravity and each being connected to one of said shoes and a stop co-operating with said base for limiting movement of said field member towards said drum, said stop insuring 55 substantially equal movements of said brake shoes by said electromagnet.

4. The combination with a brake drum and opposed brake shoes therefor, one of the same having a supporting lever of an 60 electromagnet having pivoted armature and

field members, said members tending to move towards said drum under the influence of gravity and the former being directly connected to one of said brake shoes and the latter having a link connection with said lever and a stop associated with said field member for limiting movement thereof towards said drum during brake release, said stop insuring substantially equal movements of said brake shoes by said electromagnet. 70 75

5. The combination with a brake drum and opposed brake shoes therefor, one of said shoes having a supporting lever of an electromagnet having concentrically pivoted armature and field members tending to move 80 towards said drum under the influence of gravity, one of said members supporting another of said brake shoes and having a stop associated therewith for limiting movement thereof towards said drum and the other of said members having a connection with said lever and a spring associated with said armature and field members to spread the same, said stop functioning to insure substantially equal movements of said brake 85 shoes by said electromagnet.

6. In a brake, the combination with a brake drum and opposed brake shoes therefor, of a supporting lever for one of said shoes, an electromagnet arranged adjacent 90 the periphery of said brake drum and provided with armature and field members tending upon brake release to move towards said drum, one of said members being operatively connected to said supporting lever and the other member serving to support the other of said brake shoes and a stop associated with said latter member for limiting movement thereof towards said drum. 100

7. The combination with a brake drum and opposed brake shoes therefor of actuating means for said brake shoes including an electromagnet and operative connections between said brake shoes and relatively movable parts of said electromagnet, said 110 electromagnet being mounted above said drum with its axis substantially perpendicular to the axis of said drum and a stop associated with one of said magnet parts for limiting movement thereof towards said 115 drum said stop being adjustable to provide substantially equal movements of said brake shoes by said electromagnet.

8. The combination with a brake drum and opposed brake shoes therefor, of actuating means for said brake shoes including an electromagnet having a pivoted armature member supporting one of said brake shoes, said electromagnet tending to move 120 towards said drum under the influence of gravity and a stop associated with one of said magnet parts for limiting movement thereof towards said drum, said stop affording substantially equal movements of said 125 brake shoes by said electromagnet. 130

9. The combination with a brake drum and opposed brake shoes therefor of actuating means for said brake shoes including an electromagnet having concentrically pivoted armature and field members each of said members being connected to one of said brake shoes and tending to move towards said drum under the influence of gravity and a stop associated with one of said members for limiting movement thereof towards 10 said drum, said stop affording substantially equal movements of said brake shoes by said electromagnet.

In witness whereof, I have hereunto subscribed my name.

BERNHARD E. FERNOW, JR.
